UNITED STATES PATENT OFFICE.

STANLEY W. NICHOLSON, OF TOLEDO, OHIO, ASSIGNOR TO THE DURA COMPANY, OF TOLEDO, OHIO, A CORPORATION OF DELAWARE.

HANDLE MOUNTING FOR WINDOW REGULATORS.

Application filed May 20, 1921. Serial No. 471,222.

To all whom it may concern:

Be it known that I, STANLEY W. NICHOLSON, a citizen of the United States of America, residing at Toledo, in the county of Lucas and State of Ohio, have invented certain new and useful Improvements in Handle Mountings for Window Regulators, of which the following is a specification, reference being had therein to the accompanying drawings.

10 This invention relates to handle mountings for window regulators, and more particularly for control mechanisms for motor vehicle windows.

15 The invention consists in the structural features and arrangement of parts herein-after described and illustrated in the accompanying drawing, wherein:

20 Figure 1 is a view partly in section of a handle and gearing through which said handle is adapted to actuate a window regulator, (not shown);

Figure 2 is a front view of the same;

25 Figure 3 is an end view of the gear to which said handle is coupled.

30 In these views, the reference character 1 designates a board which may be an element of a motor vehicle body (as, the lock-board of one of the doors), 2, a two-part bearing member mounted in the board 1, and 3 and 4 a pair of enmeshed spiral gears, transversely journaled in the member 2, the gear 4 being coupled to a handle 5 to be driven by the latter. The bearing member 2 is suitably chambered to accommodate the gears 3 and 4. The handle 5 has a journal portion 6, a bearing for which is formed by the hub 7 of an escutcheon plate 8. Said plate is secured to the two-part member 2 by screws 9, and the interior trimming 10 of

40 the vehicle body (of which the board 1 is a part) is engaged between the escutcheon plate and the member 2. Since the thickness of the trimming varies for different installations, it is desirable to provide a drive from the handle 5 to the gear 4 that will allow a variation within reasonable limits of the spaced relation of the handle and escutcheon plate to the mounting 2. Such a drive is established by the coupling member 11, 45 having the nature of a short rod or pin having enlarged polygonal heads 11^a upon its ends. The stub shaft 12 of the gear 4 and the journal portion 6 of the handle are respectively formed with opposed polygonal sockets corresponding in shape and size to

the heads 11^a, which loosely engage in said sockets. The socket 13 of the handle is relatively deep and receives the coupling member 11 for a major portion of its length. A spring 14, coiled in the socket 13 between the bottom thereof and the adjacent end of the coupling member, urges the latter constantly into driving engagement with the gear 4 and insures against any rattling of said coupling member. In addition to forming a journal bearing for the handle member, the escutcheon member 7, 8, holds said handle in a fixed spaced relation to the bearing member 2, this being effected by the engagement of annular shoulders 15 formed respectively internally of the escutcheon hub 7, and externally upon the handle journal portion 6. Said shoulder upon the latter portion may be produced after the escutcheon is engaged with said portion by slightly upsetting the end of said portion.

Owing to the fact that the gear 4 and handle member 5 are separately journaled, the establishment of accurate axial alignment between said gear and handle would prove difficult, and would undesirably increase the time necessary both for machining and assembly. In the absence of accurate axial alignment, a drive connection affording a certain amount of universal movement is essential to prevent binding or undue friction. The drive connection established by the member 11 is in a limited sense a universal joint, said member being sufficiently free relative to the coupled parts to assume any such slight inclination to the axes of said parts as may be required by an absence of accurate alignment between the same.

What I claim as my invention is:

1. In a device of the character described, the combination, with a handle and a member rotatably actuatable by said handle, said handle and member being formed with opposed polygonal sockets, of a coupling member having polygonal ends loosely engaging in said sockets, reduced in diameter intermediate said polygonal ends, and means independent of said coupling member maintaining the opposed relation of said handle and actuatable member.

2. In a device of the character described, the combination with a bearing member, a gear journaled in said member, an actuating handle for said gear having a journal portion, an escutcheon member engaging said

journal portion and rotatively mounting the handle upon said bearing member, and a coupling establishing a drive connection between said handle and gear, capable of a 5 limited universal movement.

3. In a device of the character described, the combination with a handle and a member rotatably actuatable by said handle, said handle and member being formed with opposed 10 polygonal sockets, of a coupling member hav-

ing polygonal ends loosely engaging in said sockets, said member being free to assume an angular relation to the axes of said handle and driven member, and means independent of said coupling member maintaining the 15 opposed relation of the handle and driven member.

In testimony whereof I affix my signature.

STANLEY W. NICHOLSON.
